COMBUSTION HEATING INSTALLATION

Charles Colombi and Louis Monney, Lausanne, Switzerland, assignors to the firm Recomatic S. A., Geneva, Switzerland, a firm of Switzerland

Application June 6, 1939, Serial No. 277,728
In Switzerland June 15, 1938

4 Claims. (Cl. 236—93)

The present invention relates to combustion heating installations having a flue for the hot gases and more particularly to draft regulators for like combustion apparatus wherein said flue provides a lateral aperture which can be closed by means of at least one rotatable damper so as to vary the draft in the flue.

It is an object of the invention to provide a device which in dependence of a flue thermostat limits the travel of the above mentioned rotatable damper in a manner that the opening of the damper is a function of the gas temperature.

A further object is the provision of a locking device which is adapted to keep the damper in closed position during the starting period of the combustion in spite of an intense draft, as long as the gas temperature has not reached a predetermined value which can be varied by adjusting the device.

These and other objects will be apparent from the following description and claims, reference being had to the accompanying drawings where-
in:

Figures 1 and 2 are respectively a schematic elevation and a plan view, partly in section, of a first embodiment of the present invention.

Figure 3 is an elevation of a second embodiment and Figures 4 and 5 are respective sections along lines 4—4 and 5—5 of Fig. 3.

Figure 6 is a plan view of a detail of the second embodiment.

The embodiment illustrated in Figures 1 and 2 comprises a chimney flue 1 having a lateral aperture 2 which communicates to the interior of a casing 3 having in one of its walls an aperture 4. A damper 5 mounted on an axle 6 pivoting in 7 and 8 on the casing 3 is adapted to close this aperture 4. On the lower portion of the axle 6 is secured a lever 9 having two arms 10 and 11. At the arm 10 a coil spring 12 is hooked in, the other end of which is fixed to a screw 13 engaged in a nut 14 integral with the wall of the casing.

A bimetal blade 15 extended within the flue 1 is secured on a bracket 16 of the casing 3. The free end of this blade 15 is hingedly connected with a rod 17 which in turn by means of a deformable member 18 is coupled with a second rod 19. This rod 19 which is slidable in a bearing in the casing while being guided between four pins 21 fixed on the casing, carries at its end a cross piece 22 which cooperates with the arm 11 of the lever 9.

The operation of the represented installation is the following:

The damper 5 submitted to the action of the spring 12 constantly tends to close the aperture 4. As soon as a sufficient depression is created by the draft in the flue, the damper opens against the action of the spring 12 for giving passage to a certain quantity of air. This opening of the damper, however, is limited by the cross piece 22 whereagainst the lever arm 11 will abut. The position of the cross piece depends on the deformation of the bimetal blade 15, in consequence of the temperature of the gases passing through the flue. When the gas temperature increases, the blade grows longer in the upward direction of Fig. 1, the cross piece 22 moves off the end of the lever arm 11 and permits travel of this arm, and consequently an opening motion of the damper 5, which is all the more important as the gas temperature is more elevated. This travel limitation of the damper is useful for the case that the depression in the flue is great and the temperature of the gases is low, as it may happen during the starting of a boiler for instance, so that the damper cannot open and the draft is maintained at a maximum until the combustion has reached a desired state; then the gases become hot and the blade 15 permits the opening of the damper for regulating the draft.

On the other side, if the depression in the flue reaches, on account of atmospheric conditions, a value near to zero and tends to become positive, the damper will be closed and will thus prevent any flowing back of the gas into the room.

The value of the depression for which the damper begins to open can be regulated by the tension of the spring 12.

The spring 12 could be replaced by a spiral spring, one end of which would be secured to the wall of the casing and the other end to the axle of the damper.

In certain embodiments wherein the opening section of the aperture must be large, two dampers can be provided and symmetrically disposed with respect to the rod 19 and each shutting an aperture of the casing. The cross piece 22 provides in this case two arms, each co-operating with a lever mounted on the axle of each of the dampers in a manner that a single bimetal blade 15 is adapted to limit simultaneously the opening of the two dampers.

The device for the travel limitation of the damper is arranged in a way to allow the thermostatic blade to freely bend under the influ-

ence of an elevated gas temperature without being subjected to permanent deformation.

The embodiment shown in the Figures 3 to 6, inclusive, comprises a flue 25 for the hot gases, having a lateral aperture 26 on the borders of which a rectangular underframe 27 is fixed by means of iron dowels 28. On this underframe 27 is mounted by means of bolts 30 a frame 29 which provides several apertures 31 separated by intermediary walls 32 whereacross the interior of the flue 25 communicates with the exterior side. A damper 33 is pivotally mounted in 34 and 35 on the frame 29 for shutting the apertures 31. This damper constantly tends under the effect of its own weight to close the apertures 31.

The underframe 27 provides at its lower part an aperture 36, wherethrough passes a support 37 which is secured to the frame 29 by means of bolts 38. The portion 39 of this support extends towards the interior of the flue and its end 40 is rectangularly bent up and shows two holes 41 wherein two parallel, cylindrical metal rods 42 can slide. Each of these rods which extend horizontally into the flue and penetrate with their outer ends the support 37 through two holes 43, is formed of two stumps provided with screw threads for being screwed together. Furthermore the outer end of the two rods 42 are secured together by means of a metal disc 44. The other, inner ends of the rods 42 are fixed in a metal plate 45 whereon is mounted a thermostat 46 constituted by three bimetal blades 47, 48 and 49, whereby the two latter serve as stiffening blades. The rectangularly bent end 50 of the blade 47 is perforated and a metal rod 51 is hooked therein. This rod 51 is threaded and screwed into a plate 52 which is fixed to an elastic metal blade 53 mounted in 54 on the support 37. The rod 51 is thus elastically guided for moving under the effect of the deformation of the blade 47. The plate 52 co-operates with a nose 55 integral with the damper 33 in a way that a traction of the rod 51 upon the plate 52 determines the closing of the damper.

The above mentioned disc 44 is provided with a threaded central bore wherethrough is screwed a rod 56 disposed outside the flue and carrying a knurled button 57 at one end, while the other end provides a neck 58 wherein is engaged a tappet 59 secured to the support 37 and preventing the rod 56 to be axially displaced. By turning the knurled button 57 the disc 44 is moved along the rod 56.

The disc 44 carries an index 60 registering with a scale 61 on a piece 62 which is secured to the support 37.

At the starting of the heating installation the damper 33 is kept in closed position under the effect of the cold blade 47 which exerts a traction upon the plate 52. As soon as the temperature of the gases has reached a sufficient value, the blade 47 bending towards the aperture 26 disengages the nose 55 and permits the damper to open over a certain angle under the influence of the depression within the flue for admitting atmospheric air in order to reduce the draft.

The initial position of the blade 47 can be varied by the displacement of the rods 42 in their guiding holes 41 and 43, which is obtained by turning the knurled button 57. An anti-clockwise rotation of this button displaces the rods upwards in Fig. 4 and the blade 47 bends because its end is kept stationary by means of the plate 52 bearing against the nose 55 of the damper 33.

which is closed. The gas temperature, therefore, must reach a higher value before the plate 52 disengages the damper than if the bimetal blade 47 would have been straight at the start. Consequently, it is possible by manipulating the regulating device to determine in advance the degree of the combustion at which the installation must work, and which will be indicated on the graduated scale 61 by means of the index 60.

If the flue 25 is of large dimensions, the rods 42 can be elongated by adjoining one or several rod stumps provided with screw threads for being screwed together so that the blade 47 is always positioned in the neighbourhood of the center of the flue.

The above described installations present the advantage of permitting the regulation of the draft in the flue while eliminating every risk that the gases flow back into the rooms, which could happen by the existence of overpressure in the flue due to a sudden change of the atmospheric conditions.

We claim:

1. Draught regulator for combustion heating installation, in combination with a flue having a lateral aperture for admission of atmospheric air, of a damper mounted on the flue to more or less open said aperture under the influence of depression existing in the flue, a straight thermostatic blade disposed entirely within the flue to be directly affected by the temperature of the hot flue gases, a rod movable along its axis and being mechanically connected at one of its extremities to the thermostatic blade, and a movable arresting member connected to the other extremity of said rod for limiting the distance of travel of the damper in function of the flue gas temperature.

2. Draught regulator for combustion heating installation, in combination with a flue having a lateral aperture for admission of atmospheric air, of a damper mounted on the flue to more or less open said aperture under the influence of depression existing in the flue, a support displaceably mounted on the flue wall, a straight thermostatic blade disposed entirely within the flue to be directly affected by the temperature of the hot flue gases, said blade being secured to one end of said support and extending in a transverse direction with respect to the direction of displacement of said support, a rod movable along its axis and being mechanically connected at one of its extremities to the thermostatic blade, a movable arresting member connected to the other extremity of said rod for limiting the distance of travel of the damper in function of the flue gas temperature, and an operating organ outside the flue and cooperating with the other end of said support for displacing the same on the flue wall with a view to modify at any time the position of the thermostatic blade and to regulate, in this way, the acting temperature of the flue gases above which the movable arresting member allows the damper to open.

3. Draught regulator for combustion heating installation, in combination with a flue having a lateral aperture for admission of atmospheric air, of a damper pivotally mounted on the flue to more or less open said aperture under the influence of depression existing in the flue, a support on the flue wall comprising two parallel slidable rods extending through said wall into the flue, a plate secured to the adjacent inner ends of said rods and a disc fixed to and connecting the adjacent outer ends of said rods, a straight thermostatic blade mounted upon the plate of said

support within the flue to extend in a transverse direction with respect to the direction of displacement of said support while being entirely exposed to the temperature of the hot flue gases, a rod movable along its axis and being mechanically connected at one of its extremities to the thermostatic blade, a movable arresting member connected to the other extremity of said rod for limiting the distance of travel of the damper in function of the flue gas temperature, and an operating organ outside the flue and cooperating with the disc of the support for sliding said support on the flue wall with a view to modify at any time the position of the thermostatic blade and

to regulate, in this way, the acting temperature of the flue gases above which the movable arresting member allows the damper to open.

4. Draught regulator according to claim 3,
5 wherein said operating organ includes a threaded stem rotatably mounted in the flue wall and provided with a manipulating button, and wherein the disc of said support is internally threaded to engage the external thread of said stem so that
10 by turning the manipulating button the disc travels along said stem and entrains said support.
